UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

SEWING MACHINE.

Application filed April 25, 1925. Serial No. 25,753.

This invention relates to sewing machines; and more especially to sewing machines wherein a barbed needle is operated normally to advance through the work to receive a 5 thread loop and to retract to draw such loop through the work, with a cooperating looper operated to place the thread in the barb of the advanced needle, and with a take-up for drawing tight the successive stitches, such 10 machines usually comprising a power operated stitching shaft and timed connections from the shaft for actuating the needle, looper and other instruments in harmony through cycle after cycle during normal stitching operations. An example of such machines is the 15 shoe stitching machine known as the welt-and-turn machine, in which the barb needle is curved and swings about a center in its advancing and retracting movements. The 20 prior patent of Schoenky 1,420,580 of June 20, 1922, and the prior patents therein referred to, are examples of the specific type of machine referred to.

The general object of the present invention is to improve the operation and convenience of sewing machines of the kind referred to, and a specific object is to provide means operative upon the stoppage of the machine for causing the needle to undergo an 25 abnormal stroke, for example by shortening the advance stroke, so that the barb will not receive a loop from the looper, and so that when the machine is finally stopped with the needle fully retracted the work can be readily 30 removed without hindrance from the needle or thread. The prior Patent 1,420,580 referred to shows one form of mechanism for accomplishing this object, and said patent may be referred to for the disclosure of many 35 details unnecessary to the description of the present improvement. It is an object of the present invention to simplify the needle actuating connections as shown in said Patent 40 1,420,580, as well as the mechanism for changing the needle stroke from normal to abnormal during the final cycle or when stopping the machine, and to render the same more effective in operation, durable, and convenient in use.

To the attainment of the objects and advantages referred to the present invention consists in the novel sewing machine and the novel features of combination, arrangement and structure herein illustrated or described.

The invention might be embodied in number-

less mechanical forms, but by way of illustration, the accompanying three sheets of drawings are presented showing a welt-and-turn shoe stitching machine embodying the invention in an advantageous specific form.

Fig. 1 is a right elevation of the upper part of such a shoe stitching machine, with many parts omitted which have no reference to the needle actuation or control; the parts being shown in final stopped position, with the needle fully retracted from the work.

Fig. 2 is a partial view similar to Fig. 1, but showing the parts in an earlier stage, preceding the stoppage, but with the needle retracted.

Fig. 3 is a top plan view of certain parts shown partly in section substantially on the line 3—3 of Fig. 1.

Fig. 4 is a rear elevation of the parts shown in the other figures.

Fig. 5 is a right elevation corresponding partly with Fig. 1, but showing the mechanism in full running condition, with the needle fully advanced.

Fig. 6 is a partial front elevation showing particularly the connections to the stop motion, the stop motion itself being omitted except for the control or pedal rod, which may correspond for example with my prior Patent 1,532,634 of April 7, 1925, referring to stopping and starting mechanism for shoe stitching machines.

The preferred operation of a mechanism of the class hereof is substantially that when the pedal is released by the foot, or other control means operated to apply the stop motion, the actual stoppage will be delayed for a complete stitch cycle or longer, during which certain operations automatically take place. For example at a certain point in the stitch cycle a readjustment of the needle connections will be effected so that the final advancing stroke of the needle will be shortened, the stop motion thereafter coming into effect so that when the needle is fully retracted the machine will come to a final stoppage with the needle disengaged both from the work and from the thread, so that the work can readily be extracted; and with the present embodiment the final stoppage is accompanied by a restoration of the needle actuating connections to normal condition, so that the machine is in readiness to be restarted, or can be turned by hand and afford the usual sequence of operation.

A complete illustration of the various stitching instruments is unnecessary but the drawings show the work rest or bumper A, supported at the front end of its shank a, constantly pulled by spring a', and having means to lock it forward at certain times, as is well understood. The curved barb needle C is shown mounted on a carrier c, turning about a center c'. A needle guide C' is shown; 10 also a looper D, operated to move around the needle path in a well known manner.

The machine frame may comprise an upright post 10 extending from the power connections at the floor to the head of the machine, and one or more fore and aft frame walls, such as the left wall 11.

The stitching or operating shaft 13 takes its bearings in the frame wall 11 and elsewhere, and at the left or outer side of the wall 20 the shaft is provided with a cam disk 14, while at the right or inside is shown a crank 15. While there may be other cranks and other cam disks these two suffice for the operations of the mechanism of the present invention.

25 The needle oscillating connections may include a pitman 17 on the crank 15, the free end of the pitman guided by an arm 18 fulcrumed at 19, and a link 20 extending from the junction of the pitman and arm to the main needle lever 21, the hub 22 of which is mounted on a rear axle 25, and the forward end of the lever vibrating upwardly and downwardly as actuated by the crank. A curved link 23 is shown extending to an arm 24 secured to the 30 needle carrier or block c.

A special arrangement consists of a fulcrum block 26 on the axle 25 arranged slidably within a curved slot 27 in the hub 22 of the needle lever. The normal position is 40 as shown in Figs. 1 and 5, but when the abnormal operation takes place, as already referred to, the needle lever hub 22 is caused to drop to the position shown in Fig. 2, which manifestly operates to shorten the final advance needle stroke. This arrangement constitutes a substantial simplification over the compound needle lever arrangement shown in Patent 1,420,580.

45 The upward and downward adjusting movement of the needle lever hub 22 may be effected through a link 30. This link extends downwardly and has pivoted to its lower end a latch finger 31 which extends upwardly to the rear and is there provided with a latch or hook 32, having a rear extension 33 by which it may be unlatched; a spring 34 acting to press the finger rearward toward latching position. The lower end of the link 30 is also provided with a stud or roller 35 adapted to move along a guide or cam slot 36 formed in a special bracket or wall 37 which also serves to support a hardened steel latch piece 38 arranged to be normally engaged by the latch 32, as seen in Figs. 1 and 5. 55 When the latch is unlatched, in a manner

to be described, the stud 35 is free to move along the cam slot 36. A spring 40 pulls forwardly on the link and stud and thus causes the stud to travel along the slot, which extends at a downward slant, increasing in 60 steepness as shown, so that when the parts reach the position shown in Fig. 2 the needle lever hub is pulled down to its lowest position, thus effectively shortening the needle stroke. It will thus be seen that the readjustment of the needle lever from normal to abnormal condition is effected by the pull of the spring 40 moving the stud 35 and link 30 downwardly in the slot 36.

65 The timing of such readjustment of the needle lever may be controlled by suitably controlled means for unlatching the latch finger 31 at the proper point of time. As seen in Figs. 1, 3 and 5 an upstanding finger 42 is arranged to press upwardly against the latch extension 33 to lift and disengage it from the latch piece 38. The extremity of a spring 43, coiled around the pivot of the unlatching finger 42, operates always to press the latter forwardly into operative position. The unlatching finger is pivoted to a supporting lever 44 which extends forwardly and is fulcrumed at 45 so that its rear end may swing up and down for unlatching operations. The middle part of the supporting lever 44 is provided with a fulcrum 47 on which is pivoted a control lever 48. This lever has a rear extension 49 formed with a slot 50 which normally, as seen in Fig. 5, is substantially concentric with the axle 25, for purposes to 70 be described. Near the front end of the control lever 48 is shown a laterally extending guard pin 51.

75 The connections for effecting the unlatching operations, through the described levers 44 and 48, may comprise a stud 52 carried on a lever 53 and arranged to vibrate forwardly and rearwardly in the curved slot 50 in the control lever 49. The lever 53 may be oscillated in proper harmony with the other operations by the following connections. The upper end of the lever 53, above the fulcrum axle 25, is formed into an arch 54, which, as seen in the rear view of Fig. 4, extends back to the axle or rather to a sleeve 115 55 surrounding the axle and extending outwardly through the wall 11, where the sleeve carries a rock arm 56 connected by a link 57, as shown also in dotted lines in Fig. 1, with a bell crank lever 58 carrying a roller or follower 59 engaged in a cam groove 60 in the cam disk 14. By this arrangement the cam 60 operates to swing the lever 53, and its stud 52 moves in the slot 50 of the control lever 48, normally without effect, since, as seen in Fig. 5, said slot is normally concentric with the fulcrum axle 25. Normally therefore the motions of the lever 53 can not effect any motions of the supporting lever 44 or the unlatching finger 42. When the readjustments 120 60

take place, which will be described, the lever 53 will effect unlatching of the latch 31 at the proper point of time.

The position of the slotted control lever 48, fulcrumed on the supporting lever 44, may be controlled in the following manner. A link 62 with spherical ends is shown engaged at its top end with a socket at the underside of the lever 48, while its lower end engages 10 a socket in a lever 63, seen in Figs. 1 and 6. A spring 64 pulls the lever 48 toward the lever 63, thus making the link 62 effective, while permitting universal motions. The lever 63 is shown as a horizontal lever arranged 15 below the head of the machine, pivoted near its center, and extending to the left, where its slotted extremity 65 engages with the stud at the right end of a lever arm 66, the other arm 67 extending to the left, where its slotted extremity engages a pin 68 20 mounted on the upright pedal rod 69. The elements 67, 68 and 69 may be pulled upwardly by any sort of spring, indicated at 70. The pedal rod extends above the lever 67, 25 its extension 71 passing to and controlling the operation of a stop motion, for example the stop motion as is fully shown and described in said Patent 1,532,634, in which the pedal rod 24 corresponds with the pedal rod 69 hereof, said stop motion operating to bring 30 the stitching shaft to a shockless stop but continue the motion to a definite final position, with the needle fully retracted from the work.

When the pedal is wholly released the 35 pedal rod and connected parts will first rise to an intermediate point, stopped by a guard 75 to be described, the stop motion not taking effect until the guard releases the parts to permit a completion of the movement. The 40 partial rise of the pedal rod causes the link 62 to lift the front end of the lever 48. This shifts the lever 48 from the position shown in Fig. 5 to a position slightly lower than that shown in Fig. 1, and with the guard pin 51 45 of the lever 48 in contact with, and held down by a guard bolt 75, or rather the lateral flange 76 thereof, as will be understood by the relation of these parts shown in Fig. 5. The guard bolt is shown as a sliding member extending 50 forwardly and rearwardly. It has a positioning pin 77 normally contacting the bearing or slideway 78, while a spring 79 pulls the bolt rearward, the bolt having a rear extension or pin 80 which slides in a portion 55 of the bracket 37 and projects into the slot 36, so that when the stud 35 is pulled forward to the lowest point of the slot 36 the stud will strike the pin 80 and force the guard bolt forward from above the guard pin 51, thus 60 releasing the latter and permitting a further upward movement of the lever 48, namely to the position shown in Fig. 1, so as to raise the unlatching finger 42 to an abnormally high position.

From this description the operation will

be understood, but may be preferably restated as follows. While the pedal is held down the stitching proceeds, the speed sometimes being regulated by slight variations in position of the depressed pedal. When the 70 pedal is released by the foot it rises to an intermediate point, being stopped by the contact of the guard finger 51 of the lever 48 against the flange 76 of the guard bolt 75. Fig. 5 shows the normal position with the 75 pedal down and from this figure will be understood how the guard 75 confines the pin 51 against completely rising. The holding down of the pedal prevents the stop motion becoming operative. The partial rising of 80 the lever 48 however throws down its rear extension 49 from the Fig. 5 position to that of Fig. 1, rendering the slot 50 eccentric. Thereupon the pin 52, vibrating in the slot, on its next rearward stroke, forces upwardly the 85 rear ends of levers 44 and 48. The unlatching finger 42 is thereby thrust upwardly from the Fig. 5 position and dislodges the latch 32 from the latch piece 38. The spring 40 at once asserts itself tending to pull the link 90 30 from the position shown in Figs. 1 and 5 to the position shown in Fig. 2. This motion, however, is controlled by the lever 53, the stud 35 bearing against the lever and moving forwardly as permitted by the return 95 forward stroke of the lever. When the stud 35 reaches its full forward position, as seen in Fig. 2, it strikes the pin 80 of the guard 75 and thereby releases the guard pin 51 on the 100 lever 48. This in turn, by releasing the lever 48, releases the pedal rod, which is thereupon forced upwardly to the full extent, thus rendering operative the stop motion. The rotation of the parts continues until the stop motion has brought the shaft to rest with the 105 needle fully retracted. In this final movement the lever 53, swinging rearwardly to its final stopped position, as seen in Fig. 1, forces the stud 35 rearwardly in the cam slot 36, thus elevating the stud, and at the same time restoring the needle lever 21 to normal condition, and applying the latch 32 to the latch piece 38, the unlatching finger 42 taking the 110 final position as seen in Fig. 1. The parts are now in normal position ready for restarting. The lever 48 will be restored to its original position when the pedal is depressed, and the lowering of the guard pin 51 will release the guard 75 and permit it to resume its initial position, while the lowering of lever 44 115 pulls down the unlatching finger to operative position; so that restarting the machine resets the mechanism for stopping.

It will thus be seen that there has been described a sewing machine of the class referred to embodying the principles and attaining the objects of the present invention. Since many matters of combination, arrangement, structure and form may be variously modified without departing from the 120 125 130

principles it is not intended to limit the invention to such matters except so far as specified in the appended claims.

What is claimed is:

- 5 1. In a power driven chain stitch sewing machine, a main shaft, stitch forming means including a barb needle and means for applying thread to the needle barb when advanced, a needle actuating lever, connections from the shaft for vibrating the lever to advance and retract the needle in cooperation with the thread applying means, said lever having its hub shiftable at the fulcrum, resilient means for shifting such hub to modify the movement communicated to the needle whereby it will avoid taking thread, a latch holding the hub in normal position, stopping means for stopping the machine with the needle retracted, means for unlatching said latch when stopping the machine, thereby allowing the resilient means to shift such hub, a pedal controlling the power drive, with connections to operate the stopping means on the release of the pedal, a guard delaying the action of the stopping means on the release of the pedal, and a connection whereby the action of shifting the needle lever hub renders said guard inoperative. 70 75 80 85
- 10 2. In a sewing machine an operating shaft, a barbed needle, actuating mechanism operated from the shaft to advance and retract the needle, means to apply thread to the advanced needle, said actuating mechanism being adjustable to modify the needle stroke to avoid taking thread, a stop mechanism for bringing the shaft to rest with the needle retracted, a controller operable to apply said stop mechanism, a guard preventing full movement of the controller, adjusting means for adjusting the needle actuating mechanism to abnormal, a latch means holding said actuating mechanism in normal adjustment, connections operated by 90 95 100 105 the partial movement of the controller for releasing such latch means, and means for thereafter rendering said guard inoperative.
- 15 3. In a sewing machine a barbed needle, needle actuating mechanism adjustable to abnormal to shorten an advancing stroke of the needle, a latch device normally maintaining the mechanism in normal adjustment, timed means for releasing said latch device to permit such abnormal adjustment, and automatic means restoring the parts to normal adjustment, during the succeeding retracting movement of the needle. 110 115 120
- 20 4. In a sewing machine a stitching means including barbed needle, a needle lever, means for vibrating the lever, and means for adjusting the lever to abnormal to modify the needle stroke, stopping means, connections operative when stopping the machine to cause the operation of said adjusting means, and means operating in the same cycle to cause restoration of normal adjustment as the machine stops. 125
- 25 5. In a power driven chain stitch sewing machine, a main shaft, stitch forming means including a barbed needle and means for ap-

plying thread to the needle barb when advanced, a needle actuating lever, connections from the shaft for vibrating the lever to advance and retract the needle in cooperation with the thread applying means, said lever having its hub shiftable at the fulcrum, resilient means for shifting such hub to modify the movement communicated to the needle whereby it will avoid taking thread, a latch holding the hub in normal position, stopping means for stopping the machine with the needle retracted, means for unlatching said latch when stopping the machine, thereby allowing the resilient means to shift such hub, a pedal controlling the power drive, with connections to operate the stopping means on the release of the pedal, a guard delaying the action of the stopping means on the release of the pedal, and a connection whereby the action of shifting the needle lever hub renders said guard inoperative.

6. In a power driven chain stitch sewing machine, a main shaft, stitch forming means including a barb needle and means for applying thread to the needle barb when advanced, a needle actuating lever, connections from the shaft for vibrating the lever to advance and retract the needle in cooperation with the thread applying means, said lever having a shiftable hub, a spring constantly tending to shift such hub to modify the movement communicated to the needle whereby it will avoid taking thread, a spring latch normally preventing such shifting, means for releasing said latch to permit the spring to so shift the hub, and other means for restoring and latching the parts. 90 95 100 105

7. In a power driven chain stitch sewing machine, a main shaft, stitch forming means including a barb needle and means for applying thread to the needle barb when advanced, a needle actuating lever, connections from the shaft for vibrating the lever to advance and retract the needle in cooperation with the thread applying means, said lever having a shiftable hub, a resilient device constantly acting on such hub for shifting it to modify the movement communicated to the needle whereby the needle will avoid taking thread, a latch normally holding the hub in normal position but permitting it to be moved by said resilient device when unlatched, stopping means for stopping the machine with the needle retracted, means for unlatching said latch when stopping the machine, thereby allowing the resilient device to shift such hub, and other means for returning the hub to normal when stitching is resumed. 110 115 120 125

In testimony whereof, I have affixed my signature hereto.

JOHN ROGER OLIVER.
